UNITED STATES PATENT OFFICE

HARRY J. TAYLOR, OF NEW YORK, N. Y.

TAPE HOLDER AND MOISTENER

Application filed December 8, 1927. Serial No. 238,679.

This invention relates to sealing devices and in particular to one adapted to hold a roll of sealing tape adapted for use in binding up packages thus doing away with cord and other holding agents.

A particular object of the invention is to provide a sealing device wherein may be contained a tape moistening roller, a water well in which the roller is placed and a trough in 10 which the roll of tape may rest, the trough itself being so shaped that it will allow the easy withdrawal of the tape from the roll without regard to the diameter of the roll or width of the tape.

15 A still further particular object of the invention is to provide a device of this character which may be made of porcelain of a highly glazed nature and to which may be imparted a shiny whiteness, thereby rendering the 20 device clean and sanitary.

A still further object of the invention is to provide a device of this nature in which the parts have been compacted so as to eliminate unnecessary pieces and one which is so 25 constructed that a minimum amount of material is used in the manufacture thereof.

A still further object of the invention is to provide a sealing device wherein the tape may be drawn from the roll across a moistening roller or cylinder and may be jerked back 30 to be severed by a knife positioned rearwardly of the roller so that the tape is ready for instant use.

To enable others skilled in the art to fully 35 comprehend the underlying features of my invention that they may embody the same in the various modifications in structure and relation contemplated, a drawing depicting a preferred form has been annexed as a part 40 of this disclosure and in such drawing, similar reference characters denote corresponding parts throughout all the views, of which,

Figure 1 is a view in side elevation of a sealing device constructed in accordance with my 45 invention, the tape roll being shown in full side elevation while the device itself is shown in longitudinal section to disclose the construction thereof.

Figure 2 is a top plan view of the device 50 illustrated in Figure 1 showing how the tape

may be drawn across a serrated runway under a knife and over a moistening roller.

Figure 3 is a section taken on the line 3—3 of Figure 2 and shows how the knife member is positioned on the body of the sealing device, the runway also being shown and the tape being illustrated in the position that it would occupy in passing under the knife.

Figure 4 is a section taken on the line 4—4 of Figure 2 and shows the cross sectional construction at various points in the body of the sealing device.

Referring to the drawings in detail, 5 indicates generally the body of the sealing device which is constructed of a single, solid 65 piece of porcelain made from a very high grade of clay and highly glazed. This is produced by pressing the mud in a die and glazing the same in a kiln to a shiny, white brightness. The under side of the base 5 is 70 provided with a cut-out 6 whereby the weight of the device is reduced to a minimum, the upper surface of the device being provided with a suitable tape holding trough 7 and forwardly thereof with an under-cut runway 75 8, the runway being provided with a transversely serrated surface 9. The expression "under-cut" in this instance meaning that the upper edges of the serrations are below the plane of the edges of the base, thus providing 80 at the opposite longitudinal sides of the device and adjacent the forward edge of the runway, the overhanging flanges 10, it being understood that these flanges 10 are provided at the forward reaches only of the runway 85 while the remainder of the device in those portions illustrated by the numeral 11 are the same width from the ends of the flanges 10 to the rear end of the device. These flanges 10 are arranged to receive a knife or cutting 90 member 12 whose ends 13, as illustrated in Figure 3, are bent down over the flange 10 so that the knife can be slid along the flanges for adjustment of its cutting edge relatively 95 to the moistening roller. The forward portion of the base is cut out to provide a rectangular well 14, the side walls thereof being provided with axle receiving grooves 15 and through the medium of which there may be positioned within the well 14, a suitable mois-

100

tening roller 16. This roller is also made of vitreous material to match the body of the sealing device and the roller has secured therein, an axle 17 which is preferably made of nickel plated brass in order to avoid rusting. The well is usually provided with water 18 and it will be noted that the side of the well nearest the runway 8 provides a dividing wall 19, this wall being bevelled on the side thereof adjacent the runway as at 20 so that the tape, which is indicated by the numeral 21, may be guided up out of the runway 8, between the knife edge and the bevelled wall 20, hereinbefore referred to.

15 It will be noted that the serrations are of substantially rectangular formation but any shaped serrations may be used to provide a runway over which the tape may be fingered without adhering to the surface of the runway should the same be wet, as it is to be understood that the tape must be drawn upwardly over the roll after it has been severed after each sealing operation.

15 The hollow trough 7 which accommodates the tape roll 21 is curved to accommodate the circumference of a roll substantially 500 feet or less in length and is so designed that the effort required is practically the same as the roll decreases by use. The trough is also designed so that the roll will not get out of the trough by its rolling action.

It is to be understood, that if desired the cutter 12 may be sharpened at its forward edge to facilitate the severing of the tape although any thin piece of metal particularly adapted to the purpose, it is believed, would be thin enough to effectively sever the tape. This cutter is made of nickel plated brass preferably in order to avoid rusting.

40 It will be noted that openings 22 have been cast in the bottom surface of the base 5 at the corners thereof and into the openings 22 may be inserted suitable rubber feet 23 or other cushion members which will not permit the sealing device to mar the surface of the furniture upon which it rests, such for instance, the surface of a desk or office table or store counter.

It is evident therefore, that I have provided an improved sealing device which is made up from two pieces of porcelain of a highly glazed nature which can be readily cleansed and which will remain sanitary under all conditions.

55 It is evident also that I have provided a sealing device arranged to hold a tape roll of varying diameter without in any way increasing the tension on the tape drawn from the roll due to its decreasing size and weight.

60 It is also evident that in a device of this character I have provided a serrated runway over which the tape may be fingered without danger of its adhesion to the surface over which it is drawn and in a device of this character, I have provided a cutting member

through the medium of which the tape may be severed after it has been moistened by the film of water carried by the moistening roller.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention what I claim as new and desire to secure by United States Letters Patent is:—

1. A moistening device and tape roll holder comprising a base, a tape roll holding trough at one end thereof, a well on the opposite end thereof, a runway over which the tape is drawn toward said well, said runway having a transversely serrated surface and being in a plane lower than the upper side of said base and a cutting member positioned adjacent the forward end of said runway.

2. A tape moistening device of the class described comprising a base having a tape roll trough at one end thereof, a well near the other end of the body, a moistening roller mounted in said well, the upper surface of the body having a depressed portion extending between the well and the trough and located in a plane below the plane of the upper surface of the body, the body having an upwardly beveled wall portion between the forward end of the depressed portion and the rear end of the well, the surface of the depressed portion being formed with transversely extending corrugations over which the tape is to be drawn to the moistening roller, and a combined guide and cutter comprising a strip mounted upon the upper side of the body and extending transversely thereof above the forward end of the depressed portion and with one transverse edge presented in proximity to the beveled wall portion of the body.

3. A moistening device of the class described comprising a base having a tape roll holding trough near one end thereof and a well near the other end thereof, a moistening roller rotatably mounted in the said well, the upper side of the base being provided with a depressed surface portion of less width than the upper side of the base whereby marginal portions of the upper side of the base will project above said surface portion to provide guides for the tape passing over said surface portion and to the moistening roller, the said surface portion having a series of transversely extending serrations, the said base having an upstanding wall portion at the rear wall of the well and at the forward end of the said serrated surface portion, the wall portion being bevelled.

eled in an upward direction, and a combined
guide and cutter comprising a strip-like body
mounted upon the upper side of the base in
spaced relation to the serrated surface por-
5
tion thereof and supported by the marginal
portions at opposite side of said surface por-
tion and with its forward edge in close prox-
imity to the upper edge of the said beveled
wall portion of the base.

10 In testimony whereof I affix my signature.
HARRY J. TAYLOR. [L. s.]
